(57) **CLAIM**

The ornamental design for a bicycle hub, as shown and described.

DESCRIPTION

FIG. 1 is a perspective view of a bicycle hub, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view of the bicycle hub shown in its position of use.

The broken line showing of the bicycle wheel in FIG. 8 is included for the purpose of illustrating environment and forms no part of the claimed design.
